UNITED STATES PATENT OFFICE

2,546,651

FLOOR RACK

Arthur F. O'Connor, Chicago, Ill., assignor to
Union Asbestos & Rubber Company, a corpora-
tion of Illinois

Application July 31, 1946, Serial No. 687,333

6 Claims. (Cl. 105—375)

1

This invention relates to floor racks and more particularly to lading supporting racks for railroad refrigeration cars and the like.

One of the objects of the invention is to provide a floor rack which resiliently supports the lading and in which vertical movements are damped to prevent setting up harmonic oscillations.

Another object is to provide a floor rack in which vertical movements of the lading are resiliently opposed by frictional engaging cam or wedge members.

Still another object is to provide a floor rack in which blocks of rubber-like material act through slidable wedge members to absorb the load and to damp vertical oscillation.

The above and other objects and advantages of the invention will be more readily apparent from the following description when read in connection with the accompanying drawing in which:

Figure 1 is a partial transverse section through a railway car having a floor rack embodying the invention;

Figure 2 is a partial section on the line 2—2 of Figure 1;

Figure 3 is a view similar to Figure 1 of an alternative construction; and

Figure 4 is a partial section on the line 4—4 of Figure 3.

In the construction illustrated, the railway car comprises a floor 10 and a side wall 11 which may be constructed and insulated in any desired manner. Within the car a floor rack is provided, formed by a plurality of parallel elongated stringers indicated generally at 12 which support slats 13 on which the lading may be carried. As shown, the slats 13 are formed by channel-shaped metal strips which may be perforated for ventilation although other types of slats could be used if desired.

Each of the stringers 12 is formed by a base 14 and a supporting strip 15 movable vertically relative to the base. In the form shown in Figures 1 and 2, the base comprises an elongated metal strip having upwardly turned end portions which terminate in horizontal flanges 16. The supporting strip 15 is of inverted channel shape and fits slidably over the base for vertical movement relative thereto. Separation of the supporting strip and the base is prevented by bolts 17 extending through the sides of the supporting strip and engaging the flanges 16 as shown.

The supporting strip is urged upward relative to the base by cam or wedge means includ-

2

ing wedge members 18 rigidly secured between the side flanges of the supporting strip and provided with downwardly diverging facing surfaces. Wedge blocks 19 are slidably supported on the base and have upwardly converging wedge surfaces which engage the surfaces of the blocks of the wedge members 18 so that the blocks may be moved together when the supporting strip moves down on the base. The blocks 19 are urged apart by resilient blocks of rubber-like material 21 which yieldingly press the blocks 19 into engagement with the wedge members 18.

In use, the weight of the lading supported on the slats 13 urges the supporting strip 15 downward tending to squeeze the blocks 19 together and to deform the rubber block 21. As the lading tends to bounce vertically during operation at high speeds or over rough track, the supporting strip will move up and down on the base alternating pressing and releasing the rubber blocks 21 to absorb the shock so that they will not be transmitted to the load. The vertical movements are damped by frictional movement of the wedge members 18 and the blocks 19 as well as by the inherent damping effect of the rubber material.

In order that the rack may be swung to a vertical position for cleaning of the car floor, hinge means are provided formed by brackets 22 secured to the supporting strip 15 and carrying pins 23. The pins 23 slidably and rotatably fit into elongated slots in brackets 24 secured to the side wall of the car. With this construction, the supporting strips and slats can move vertically without interference and the entire rack may be swung to a vertical position adjacent the side of the car so that the car floor can be cleaned.

In the construction shown in Figures 3 and 4, the base 14 is replaced by an elongated wooden strip or beam 25 over which an inverted channel-shaped supporting strip 26 slidably fits. A bolt 27 carried by the supporting strip slides in a vertical elongated slot in the beam 25 to limit the relative movement between the beam and the supporting strip.

The supporting strip 26 carries a series of spaced wedge members 28 which taper downwardly toward the top of the beam 25 as seen in Figure 4. A series of wedge blocks 29 are slidably supported on top of the beam 25 and engage the sides of the wedge members 28 so that the blocks between adjacent wedge members will be moved together when the supporting strip moves downward toward the beam. Preferably a wear strip 31 is provided on the beam on which the

blocks 29 may slide. The adjacent blocks are urged apart by compression springs 32 seated in recesses in the ends of the block as shown.

In use, the weight of the lading on the slats 13 urges the supporting strip 26 downward so that adjacent wedge blocks 29 will be cammed together to compress the springs 32. The frictional engagement of the wedge members 28 and blocks 29 will provide a damping action to prevent setting up of undesired harmonic oscillations.

While two embodiments of the invention have been shown and described in detail, it will be understood that these are illustrations only and not to be taken as a definition of the scope of the invention, references being had for this purpose to the appended claims.

What is claimed is:

1. A floor rack for railway cars and the like comprising a plurality of parallel elongated stringers and cross slats supported on the stringers, each stringer including a base to engage the car floor, a supporting strip movable vertically relative to the base and to which the slats are connected, wedge members carried by the base and the strip having wedge surfaces lying at an angle to the vertical so that one of the wedge members will be moved horizontally when the strip moves toward the base, and resilient means engaging said one of the wedge members yieldingly to resist such horizontal movement thereof.

2. A floor rack for railway cars and the like comprising a plurality of parallel elongated stringers and cross slats supported on the stringers, each stringer including a base member to engage the car floor, a supporting strip member movable vertically relative to the base member and to which the slats are connected, a pair of wedge members having diverging facing surfaces carried by one of the members, a pair of wedge members fitting between the diverging surfaces and movably carried by the other of the members, and resilient means between the last named pair of wedge members urging them apart.

3. A floor rack for railway cars and the like comprising a plurality of parallel elongated stringers and cross slats supported on the stringers, each stringer including a base member to engage the car floor, a supporting strip member movable vertically relative to the base member and to which the slats are connected, a pair of wedge members having diverging facing surfaces carried by one of the members, a pair of wedge members fitting between the diverging

surfaces and movably carried by the other of the members, and a block of rubber-like material between the last named wedge members resiliently urging them apart.

4. A floor rack for railway cars and the like comprising a plurality of parallel elongated stringer and cross slats supported on the stringers, each stringer including a base to engage the car floor, a supporting strip movable vertically relative to the base and to which the slats are connected, a series of spaced downwardly tapered wedge members carried by the supporting strip, wedge blocks slidably supported on the base and engaging the sides of the wedge members to be moved horizontally when the strip moves down toward the base, and resilient means yieldingly urging the wedge blocks into engagement with the wedge members.

5. In a floor rack, an elongated stringer comprising a base, a channel-shaped supporting strip fitting slidably over the base for vertical movement relative thereto, wedge members carried by the base and the strip and engaging each other so that one of them will be moved horizontally when the strip moves vertically on the base, and resilient means engaging said one of the wedge members yieldingly to resist such horizontal movement thereof.

6. In a floor rack, an elongated stringer comprising a base, a channel-shaped supporting strip fitting slidably over the base for vertical movement relative thereto, wedge members carried by the strip having downwardly diverging facing surfaces, wedge blocks movably carried by the base and engaging said surfaces to be moved together thereby when the strip moves downward on the base, and resilient means engaging the wedge blocks to urge them apart.
